UNITED STATES PATENT OFFICE.

FREDRICH J. RODE, OF CHICAGO, ILLINOIS, ASSIGNOR TO MARQUETTE TOOL & MFG. COMPANY, OF CHICAGO, ILLINOIS, A CORPORATION OF ILLINOIS.

HYDRAULIC CUSHION FOR SHEET-METAL PRESSES.

Application filed April 21, 1927. Serial No. 185,489.

This invention relates to improvements in hydraulic cushions particularly adapted though not necessarily limited in its use for sheet metal presses in which the metal is shaped by means of co-operating dies, one of which dies is reciprocable toward and away from the other, the work being clamped or held by means of a blank or work holding element that co-operates with the reciprocable die member, the blank or work holding element being resisted in its movement in one direction by the said cushion, and one of the objects of the invention is to provide an improved hydraulic cushion of this character in which a predetermined quantity of liquid is used in the cushion, the cushion embodying cylinder and piston members, the liquid being circulated from beneath the piston under predetermined conditions to relieve the pressure and then return to the pressure side of the piston for restoring the blank or work holding element.

A further object is to provide in a cushion of this character improved means for returning the liquid to the pressure side of the piston at a predetermined time in the cycle of operation of the press, and improved means for varying at will the time at which the said liquid is thus returned.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

40 The figure is a view partly in side elevation, partly broken away and partly in section of a sheet metal press having an hydraulic cushion constructed in accordance with the principles of this invention applied thereto.

45 Referring more particularly to the drawing the numeral 10 designates the bed of a press, 11 the uprights, 12 a reciprocating ram or member to which a die 13 is connected, 14 a crank shaft to which the reciprocating ram 12 is connected by means of links 15, the shaft being rotated in any suitable manner and from any suitable source of power (not shown).

50 Mounted upon the bed or bolster plate 10

is a die 16, with which the die 13 co-operates and encompassing the die 16 is a blank or work holding element 17 which is supported by means of pins 18 that pass loosely through the bed or bolster plate 10 and engage or rest upon a pressure plate 19.

55 The pins 18 are of such a length that the upper surface of the blank or work holding element 17 will be normally flush with the upper surface of the die 16 so that the work 20 may rest upon the die and blank holding member 17.

All of the above referred to parts are of the ordinary and well known construction.

60 Supported beneath the bed 10 is a support 21 which is located preferably in a pit 22 and mounted upon the support 21 is a cylinder 23, having a piston 24 reciprocable therein. The piston rod 25 passes through a suitable stuffing box 26 in the top of the cylinder 23 and is connected in any suitable manner such as by means of fastening devices 27, with the pad or plate 19.

65 A vent opening 28 may be provided in the cylinder 23.

70 Mounted also upon the support 21 are a plurality of cylinders 29, any number of which may be provided, but here shown as two, and as the construction and operation of each of these cylinders with respect to the cylinder 23 is the same, the description of 75 one will apply to them both.

75 The cylinder 23 is provided with an opening 30 in its wall and the cylinder 29 is provided with an opening 31, both of which are 80 located preferably at the base of the respective cylinders.

85 Any suitable connection may be provided between these openings and the connection is provided with a valve casing 32, having a valve 33 therein, preferably of the flap type so arranged that it will open to permit liquid to flow from the cylinder 29 into the cylinder 23 under the pressure of the liquid and will close under the pressure of the liquid to prevent the liquid from flowing from the cylinder 23 into the cylinder 29.

90 Leading also from the cylinder 29, preferably through the bottom thereof is an opening 34 connected with a pipe 35, which in turn is connected with a valve casing 36 in which a valve 37 is arranged, and this valve 37 controls an opening 38 preferably in the bottom of the cylinder 23, the pipe 35 and valve casing 36 forming a communicating 105 110

passage between the cylinder 23 and cylinder 29.

The valve 37 is controlled by a spring 39, the stress of which may be varied by means of an adjusting device 40, such as a screw. The spring 39 holds the valve 37 upon its seat under a predetermined pressure, which pressure may be varied by adjusting the device 40. The valve 37 is unseated by the stress or pressure of the liquid in the cylinder 23 beneath the piston 24, and when such pressure overcomes the stress of the spring 39.

When the ram 12 descends the die 13 will 15 co-operate with the work holder 17 to clamp the work 20. A further movement of the ram 12 in the same direction will lower the work holder 17, thereby depressing the plate or pad 19 through the medium of the pins 20 18. As the pad or plate 19 descends the piston 24 will descend in the cylinder 23 and the liquid in the cylinder 23 beneath the piston will create a resistance pressure to the movement of the piston in such direction until the pressure upon the liquid by the piston 24 overcomes the stress of the spring 39. The valve 37 will then be unseated and the liquid will flow into the pipe 35 and through the opening 34 into the cylinder 29 beneath a piston 41 in the cylinder 29. This will cause the piston 41 to rise.

In order to restore the piston 24 and the pad or plate 19 it is necessary to depress the piston 41 to force the liquid from the cylinder 29 back into the cylinder 23 beneath the piston 24 and through the opening 31, valve chamber 32 and opening 30, thereby unseating the valve 33.

As a means for thus depressing the cylinder 41 there is provided a resilient element 42 in the form of a coil spring which encompasses the piston rod 43, one end of the spring abuts the piston 41 and the other end abuts a collar 44 upon the piston rod 43. A lever 45 is pivotally mounted intermediate its ends as at 46 to a fixed support 47.

One end of the lever 45 acts upon the spring 42 through the collar 44 and the other end of the lever is provided preferably with an anti-friction roller 48.

As the piston 41 rises the spring 42 will also rise causing the collar 44 to slide over the piston rod 43, which will rock the lever 45 about its pivot to depress the end carrying the roller 48, thereby allowing the piston 41 to rise without exerting any stress of the spring 42 thereupon.

Means are provided for storing energy in the spring 42 to cause the same to become active at a predetermined time in the cycle of operation of the press so that the liquid will be forced out of the cylinder 29 and into the cylinder 23 to restore the piston 24.

Such means embodies a rod 49 which is connected with any movable part of the press

here shown as the ram 12. This rod 49 passes loosely through the bed or bolster plate 10 and also through a guide or bracket 50.

A cam 51 is adjustably mounted upon the 70 rod 49 and held in its adjusted position by means of suitable devices 52.

The cam 51 is so positioned that during the lowering movement of the ram 12 the anti-friction roller 48 will pass off of the 75 high portion of the cam just at about the time that the die 13 contacts with the work 20, thereby allowing the piston 41 to rise without exerting any of the stress of the spring 42 thereon.

When the ram 12 starts to ascend the high portion of the cam will engage the roller 48 and rock the lever 45 in a direction to store or create energy in the spring 42 and which energy serves to force the piston 41 downwardly to eject the liquid from the cylinder 29 back into the cylinder 23. The stress of the spring 42 under such conditions is preferably just sufficient to restore the piston 24 by forcing the liquid against the pressure 90 side thereof.

Obviously by adjusting the cam 51 upon the rod 49 the time in the cycle of operation of the press at which the lever 45 will be rocked to create energy in the spring 42, may 95 be varied at will.

While the preferred form of the invention has been herein shown and described, it is to be understood that various changes may be made in the details of construction and in 100 the combination and arrangement of the several parts, within the scope of the claims, without departing from the spirit of this invention.

What is claimed as new is:—

1. In a sheet metal press a pressure pad, an hydraulic cushion for resisting the movement of the pad in one direction and embodying cylinder and piston members one of which operates upon the pad, a second cylinder and piston members, a conduit for leading the liquid from the pressure side of the first said piston to the pressure side of the other piston, variable resistance means for controlling the conduit and operable 110 upon by the liquid pressure to open the conduit, a conduit for leading the liquid back from the second to the first recited cylinder, a check valve in the last said conduit, and means rendered active by a movable part of the press at a predetermined time in the cycle of operation of the press for moving the piston in the second recited cylinder in a direction to force the liquid therefrom and back into the first said cylinder to restore 115 the said pressure pad.

2. In a sheet metal press a pressure pad, an hydraulic cushion for resisting the movement of the pad in one direction and embodying cylinder and piston members one 120

of which is operable upon the pad, a second cylinder and piston members, a conduit for leading the liquid from one to the other cylinder, variable resistance means for controlling the passage, a conduit for leading the liquid from the second back to the first recited cylinder to restore said pad, a check valve for controlling the last said passage, resiliently yielding means operable upon the 5 second recited piston, means for storing energy in the said resiliently yielding means to cause the second recited piston to force the liquid through the second recited conduit, and means connected with a movable 10 part of the press for thus actuating the second recited means.

3. An hydraulic cushion for sheet metal presses embodying a pair of cylinder and piston members, two passages forming communications between the cylinders, variable resistance means for controlling one of the 20 passages and adapted to be opened by liquid pressure to permit liquid to flow in one direction therethrough from one cylinder to the other cylinder, a check valve for controlling the other passage and adapted to be automatically opened to permit the liquid 25 to flow from one cylinder to the other and in a direction opposite to the first recited direction of flow, a normally inactive resilient element co-operating with one of the pistons and being maintained inactive during the movement of the piston in one direction, a controlling member co-operating with said 30 resilient element, and means operable by a movable part of the press for creating energy in the said resilient element at a predetermined time in the cycle of operation of the press for forcing the liquid from the respective cylinder back to the other cylinder.

4. In a sheet metal working press a pressure pad, an hydraulic cushion for resisting the movement of the pad in one direction and embodying cylinder and piston members, a second cylinder and piston members, a conduit for leading the liquid from the pressure side of the first said piston to the pressure side of the second said piston to move the latter, means for moving the last said piston in the opposite direction to force the liquid back to the pressure side of the other piston to restore the latter, variable resistance means for controlling the flow of the liquid from one cylinder to the other in the first recited direction, the first said means embodying a resilient element movable with the respective piston, a shiftable element operable upon said resilient element to render the latter active at a predetermined time in the cycle of operation of the press, and means connected with a movable part of the press for actuating the said shiftable element.

5. In a sheet metal working press a pressure pad, an hydraulic cushion for resisting

the movement of the pad in one direction and embodying cylinder and piston members, a second cylinder and piston members, a conduit for leading the liquid from the pressure side of the first said piston to the pressure side of the second said piston to move the latter, means for moving the last said piston in the opposite direction to force the liquid back to the pressure side of the other piston to restore the latter, variable resistance means for controlling the flow of the liquid from one cylinder to the other in the first recited direction, the first said means embodying a resilient element movable with the respective piston, a lever mounted upon a fixed pivot, one end of the lever being operable upon said resilient element, and means connected with a movable part of the press and operable at a predetermined time in the cycle of operation of the press to swing the lever about its pivot to create energy in said resilient element to move the respective piston.

6. In a sheet metal working press a pressure pad, an hydraulic cushion for resisting the movement of the pad in one direction and embodying cylinder and piston members, a second cylinder and piston members, a conduit for leading the liquid from the pressure side of the first said piston to the pressure side of the second said piston to move the latter, means for moving the last said piston in the opposite direction to force the liquid back to the pressure side of the other piston to restore the latter, variable resistance means for controlling the flow of the liquid from one cylinder to the other in the first recited direction, the first said means embodying a resilient element movable with the respective piston, a lever mounted upon a fixed pivot, one end of the lever being operable upon said resilient element, and a cam device responsive in its movement to a movable part of the press for swinging the lever about its pivot to create energy in the resilient element to move the respective piston.

7. In a sheet metal working press a pressure pad, an hydraulic cushion for resisting the movement of the pad in one direction and embodying cylinder and piston members, a second cylinder and piston members, a conduit for leading the liquid from the pressure side of the first said piston to the pressure side of the second said piston to move the latter, means for moving the last said piston in the opposite direction to force the liquid back to the pressure side of the other piston to restore the latter, variable resistance means for controlling the flow of the liquid from one cylinder to the other in the first recited direction, the first said means embodying a resilient element movable with the respective piston, a lever mounted upon a fixed pivot, one end of the lever operating upon the resilient element, and a cam device

connected with a movable part of the press and operable during its movement in one direction to swing the lever about its pivot to create energy in the resilient element to move the respective piston, said lever being movable in the opposite direction independently of the cam and by the action of the liquid upon the last recited piston.

8. In a sheet metal working press a pressure pad, an hydraulic cushion for resisting the movement of the pad in one direction and embodying cylinder and piston members, a second cylinder and piston members, a conduit for leading the liquid from the pressure side of the first said piston to the pressure side of the second said piston to move the latter, means for moving the last said piston in the opposite direction to force the liquid back to the pressure side of the other piston to restore the latter, variable resistance means for controlling the flow of the liquid from one cylinder to the other in the first recited direction, the first said means embodying a resilient element movable with the respective piston, the first recited means embodying a rod connected with the piston, a resilient element carried by the piston and encompassing the rod, a lever mounted upon a fixed pivot, one end of the lever being operable upon the resilient element, and a member connected with a movable part of the press and adapted to engage and swing the lever about its pivot at a predetermined time in the cycle of operation of the press to create energy in said resilient element.

9. In a sheet metal working press a pressure pad, an hydraulic cushion for resisting the movement of the pad in one direction and embodying cylinder and piston members, a second cylinder and piston members, a conduit for leading the liquid from the pressure side of the first said piston to the pressure side of the second said piston to move the latter, means for moving the last said piston in the opposite direction to force the liquid back to the pressure side of the other piston to restore the latter, variable resistance means for controlling the flow of the liquid from one cylinder to the other in the first recited direction, the first said means embodying a resilient element movable with the respective piston, the first recited means embodying a rod connected with the piston, a resilient element carried by the piston and encompassing the rod, a lever mounted upon a fixed pivot, one end of the lever being operable upon the resilient element, a member connected with a movable part of the press and adapted to engage and swing the lever about its pivot at a predetermined time in the cycle of operation of the press to create energy in said resilient element, and means for varying at will the time of operation of the last said member upon the said lever.

10. In a sheet metal working press a pressure pad, an hydraulic cushion for resisting the movement of the pad in one direction and embodying cylinder and piston members, a resilient element movable with the piston and normally inactive with respect to the piston, means for forcing the liquid into the cylinder to move the piston, a member operable upon the resilient element to create energy therein to restore the piston and thereby force the liquid from the pressure side of the piston, and means operable at a predetermined time in the cycle of operation of the press to actuate the said member.

11. In a sheet metal working press a pressure pad, an hydraulic cushion for resisting the movement of the pad in one direction and embodying cylinder and piston members, a resilient element movable with the piston and normally inactive with respect to the piston, means for forcing the liquid into the cylinder to move the piston, a member operable upon the resilient element to create energy therein to restore the piston and thereby force the liquid from the pressure side of the piston, and means connected with a movable part of the press and operating upon the said member at a predetermined time in the cycle of operation of the press to cause said member to create energy in the resilient member to restore the piston.

12. In a sheet metal working press a pressure pad, an hydraulic cushion for resisting the movement of the pad in one direction and embodying cylinder and piston members, a resilient element movable with the piston and normally inactive with respect to the piston, means for forcing the liquid into the cylinder to move the piston, a member operable upon the resilient element to create energy therein to restore the piston and thereby force the liquid from the pressure side of the piston, a cam device connected with a movable part of the press and operable at a predetermined time in the cycle of operation of the press to create energy in the resilient member to restore the piston, and means for varying at will the time in the operation of the press at which the said cam will operate upon the said member.

13. In a sheet metal working press a pressure pad, an hydraulic cushion for resisting the movement of the pad in one direction and embodying cylinder and piston members, a resilient element movable with the piston and normally inactive with respect to the piston, means for forcing liquid into the cylinder to move the piston, a lever pivotally mounted upon a fixed part of the press, one end of the lever adapted to operate upon said resilient element, and means connected with a movable part of the press and operable upon the lever at a predetermined time in the cycle of operation of the

press to create energy in the said resilient element to restore the piston and displace the liquid from the pressure side of the piston.

totally mounted upon a fixed part of the press, one end of the lever adapted to operate upon said resilient element, and a cam 15 device adjustably connected with a fixed part of the press and operable upon the said lever to create energy in the resilient element to restore the piston and displace the liquid from the pressure side of the press.

In testimony whereof I have signed my name to this specification, on this 15th day of April, A. D. 1927.

FREDRICH J. RODE.

- 5 14. In a sheet metal working press a pressure pad, an hydraulic cushion for resisting the movement of the pad in one direction and embodying cylinder and piston members, a resilient element movable with the 10 piston and normally inactive with respect to the piston, means for forcing liquid into the cylinder to move the piston, a lever piv-
